L. S. GILMORE

TOURIST'S KITCHENETTE OR CABINET

Filed Sept. 16, 1922

Fig. 1.

Low Sheldrake Gilmore

INVENTOR

UNITED STATES PATENT OFFICE.

LOU SHIELDS GILMORE, OF EL RENO, OKLAHOMA.

TOURIST'S KITCHENETTE OR CABINET.

REISSUED

Application filed September 16, 1922. Serial No. 588,596.

To all whom it may concern:

Be it known that I, LOU SHIELDS GILMORE, a citizen of the United States, residing at El Reno, in the county of Canadian and State of Oklahoma, have invented a certain new and useful Improvement in Tourists' Kitchenettes or Cabinets, of which the following is a specification, reference being had to the accompanying drawings.

My invention has reference to that class of kitchenettes, or cabinets, adapted to be used in light house-keeping, but are portable and particularly designed and adapted to be securely mounted to and carried on the running-board of an automobile, but are detachable therefrom, and being of simple and economical construction, and the parts being compactly and accessibly arranged for the carrying of a large assortment of food stuffs, and for refrigeration for them and for drinking water, and are so arranged that the door or lid of the member mounted on hinges in connection with detachable legs, can be formed into a cooking table or eating table.

Other objects in view will hereinafter appear. My invention is a tourists' kitchenette or cabinet that embodies the peculiar construction and novel arrangement of parts stated in the following description, specifically pointed out in the appended claims, and illustrated in the accompanying drawings.

In order to accomplish the desired results use is made of a casing of metal, or other suitable material, a front door, a lifting or tilting top, an insulated ice-box, or holder in the top of the casing, a drinking-water tank, an uninsulated division between them, drawers, hinged lids or doors, a dripping-water tank with over-flow outlet, and other compartments in the casing.

A practical embodiment of my invention showing the peculiar construction and novel arrangements of the parts is represented in the accompanying drawings forming a part of this specification, and stated in the following description, in which characters of reference indicate like, or corresponding parts in all the views.

Figure 1 is a side view of a motor vehicle with my device applied.

Figure 2 is a perspective view of the device, on an enlarged scale, showing the same in open position.

Figure 3 is a sectional detail of the drink-

ing water compartment, with portions broken away.

Figure 1 shows the tourists' kitchenette or cabinet mounted on the running-board of an automobile, with the canopy 1 down over the kitchenette with corner rolled back, showing the faucet 2 opening out of the drinking-water compartment 28, and a drainage 3 to the drinking-water compartment; a handle 4, a canvas strap 5 with which to fasten the kitchenette to the automobile, and a bolted combined horizontal and vertical cleat or bracket 6 to further securely fasten the kitchenette or cabinet to the running-board of the automobile. The canopy 1 while the kitchenette or cabinet is "in camp" is suspended above the kitchenette or cabinet and table for protection from the sun, rain and elements.

Figure 2 shows the kitchenette or cabinet with the top or upper lid 27 elevated, and the door or lower lid 7 lowered and resting on the detachable legs 9 and 9^A, inserted into the cleats 8 and 8^A on the outer, and when opened on the under part of the lower lid or door, the door or lower lid when opened forming a work-table and also an eating-table. 10 shows the rectangular shaped dish-pan with round corners, which when not in use and when on trips, occupies with the other cooking utensils, compartment 15; in compartment 15 is also found a substantial rod or rack 17 near the top and front of said compartment and securely fastened at each end, and in-set slightly from the front, on which to hang damp or used towels, dish-towels and cloths; also a looped strap or strip 16 in which to insert pieces of cutlery, cooking utensils, etc.; suitable wires may be arranged to receive electric current from the automobile for an electric bulb to throw the light down on the work-table or eating-table.

Other compartments and parts, are: plates and pans 19; bread 20, with a lid or door for both 19 and 20, showing perforation of the door in front of the bread compartment 20 for air; face and bath towels 22, and tea-towels 23; an insulated lid for the ice-box 24; an insulated lid 25 for the drinking water compartment; a section of the front of the kitchenette removed showing the inside of the ice-chest 24^A with three or more pins 26 in the bottom of the ice-chest to assist in holding the ice in place; drinking-water 28; a dead-air space 38 between the insulation of ice-chest

and drinking-water tank, and the top lid 27 and the lower lid or door 7; a drawer 29 for the silver-ware; a drawer 30 for bacon; a compartment 31 for eggs, and a paste-board 5 egg carton or container, with a hinged lid to said compartment opening downward and outward; an open space without cover or lid 32 for papers, books, magazines, and other like articles; a drawer 11 fitting into 10 11^A being subdivided vertically into a larger division for flour and two smaller divisions for sugar and meal; fruits 33 with a hinged lid or door opening downward and outward; 15 34 for coffee, butter, crisco and milk, with hinged lid or door opening downward and outward; a compartment 35 for catching the drippings for use in camp from the melted ice through a hole in the bottom of said ice-chest over the said dripping-tank and holding 20 the said drippings until it becomes sufficiently full to reach near the top of said dripping-tank where it overflows through an open tube 37 which is open at both ends, the upper end to allow the dripping-tank to 25 over-flow and the lower end to allow it to escape at the bottom of the kitchenette or cabinet, and at or near the front thereof; in numbers 11, 12, 21, 24, 25, 29, 30, 31, 33 and 34, each and all have rings in the front to 30 further assist in the easy opening thereof.

Figure 3 shows the drinking-water compartment 28 and the inside of the ice-chest 24^A, with a hole or drip into the dripping-water compartment 35; the insulation 40 35 on the outside of and under drinking-water

compartment 28 and the ice-chest 24^A, and the uninsulated division 41 between the drinking-water compartment 28 and the ice-chest 24^A, and the drinking-water compartment 28 and the dripping-water compartment 35.

From the above description taken in connection with the drawings, the complete construction, the manner of the application and advantages of my invention will be apparent.

The detailed arrangement of parts shown and described discloses a perfect construction, yet it is understood various modifications and changes of details of structure may be made without departing from my invention as expressed in the following claim.

What is claimed is:

A device of the character stated comprising a casing, a closure at the front, a multiplicity of compartments accessible when said closure is open, a hinged top and compartments accessible when said top is opened, said compartments including an ice receptacle and a juxtaposed drinking-water container, a series of compartments intermediate the front and top compartments, and an independent closure therefor, said last-named closure being in position to be concealed by the first-named closure when closed.

Witness my hand this 7th day of September, 1922, at Oklahoma city, Oklahoma County, and State of Oklahoma.

LOU SHIELDS GILMORE.
